UNITED STATES PATENT OFFICE

140,820

DESIGN FOR A SHOE OR SIMILAR ARTICLE

Hans J. Kroto, Cambridge, Mass.

Application January 31, 1945, Serial No. 117,697

Term of patent 14 years

(Cl. D7—7)

To all whom it may concern:

Be it known that I, Hans J. Kroto, a citizen of the United States, residing at Cambridge, in the county of Middlesex and Commonwealth of Massachusetts, have invented a new, original, and ornamental Design for a Shoe or Similar Article, of which the following is a specification, reference being had to the accompanying drawing, forming a part thereof.

The single figure of the accompanying drawing is a perspective view of a shoe showing my new design.

The essential features of my design reside in the parts shown in full lines.

I claim:

The ornamental design for a shoe or similar article, substantially as shown and described.

HANS J. KROTO.
